UNITED STATES PATENT OFFICE

92,574

DESIGN FOR A LIGHT REFLECTOR

William V. Bergen and Arthur C. Shute,
Portland, Oreg.

Application September 13, 1933, Serial No. 49,250

Term of patent 14 years

To all whom it may concern:

Be it known that we, WILLIAM V. BERGEN and ARTHUR C. SHUTE, residing at Portland, in the county of Multnomah and the State of Oregon, have invented a new, original, and ornamental Design for Light Reflectors, of which the following is a specification, reference being had to the accompanying drawing, forming a part thereof.

Fig. 1 is a side view of the assembled device.

Fig. 2 is a plan view of the assembled device.
Fig. 3 is an inverted plan view of the assembled device.

We claim:

The ornamental design for a light reflector, substantially as shown.

WILLIAM V. BERGEN.
ARTHUR C. SHUTE.
